UNITED STATES PATENT OFFICE

2,678,724

CORDAGE PACKAGE

Lawrence J. Andriot, Jr., Louisville, Ky., assignor
to Puritan Cordage Mills, Louisville, Ky., a corporation

Application March 30, 1953, Serial No. 345,633

2 Claims. (Cl. 206—56)

1

This invention relates to a package for containing and handling cordage such as clothesline, sash cord or the like which may be generally arranged in the form of a pair of hanks joined together by an intermediate looped portion.

In the sale and use of such cordage the connecting looped portion of the hanks may be conveniently examined by the purchaser to determine the character and quality, and the loop further provides a convenient medium for severing the two hanks if the purchaser desires only a single length, such as 50 feet of clothesline or a double length comprising both hanks, generally 100 feet.

It is the purpose of this invention to so package the pair of joined hanks of such cordage that they may be sold, handled and carried in a single unit. But in event that the purchaser desires only a single hank, by merely severing the joining loop the carton may be readily separated into two complete individual container units or cartons, each containing a single hank. Thus a double hank package may be offered or a single hank package, complete in itself and comprising a severable unit of the double hank package.

A further feature of the invention resides in the arrangement of the end flaps of a double hank package or carton whereby the intermediate loop portion extending between the pair of hanks may protrude outwardly to serve as a carrying handle for the package or carton as well as provide an exposed section of the clothesline for inspection and convenient severance into single hank units.

The full nature of the invention will be understood from the accompanying drawings and the following description and claims:

Fig. 1 is a perspective view of the double hank clothesline package showing portions thereof broken away to expose the contents.

Fig. 2 is a perspective view of the double hank package illustrating the severable clothesline container units and the openings provided in the end flaps through which the looped handle portion of the hanks may extend.

Fig. 3 is an end plan view of the package with the end flaps in open position.

Fig. 4 is the same as Fig. 3 showing a modified form of single unit package for receiving a pair of clothesline hanks with the end flaps formed to provide openings through which the looped carrying handle may extend.

In the drawings there is shown a clothesline package comprising a pair of separable clothesline containing units or cartons, one unit con-

2

taining a hank of clothesline indicated at A and the other unit containing a hank of clothesline indicated at B. Said hanks A and B are joined by an exposed loop 10 comprising an extension of the clothesline from the pair of hanks A and B. The hank A is contained within a separable container unit C and a hank B is contained in a companion and adjacent complete container unit D. The unit C is provided with a back wall 11, an outer side wall 12, an inner side wall 13 and a front wall 14. The inner wall 13 terminates in a sealing flap 15 which is glued or similarly secured to the inner surface of the front wall 14. The unit D is similarly formed with a back wall 16, outer side wall 17, inner side wall 18, front wall 19 and inner securing flap 20. At each end of the side wall 12 of the unit C there is an inner end closure flap 21 hinged thereto having a notch to provide an aperture at its forward outer corner portion as indicated at 22. At each end of the unit D there is a similarly arranged flap 23 having a corresponding notch 24.

The front walls 14, 19 of the units are joined together along the line 25 so as to provide a common front wall for the entire package including both units. Preferably the front walls may be of integral board perforated as at 25 whereby they will be joined as a single common front wall for the package, but readily severable through the medium of the perforations 25 so that the two units may be separated into complete individual hank carrying cartons.

Each end of the front wall 14 is provided with outer end closure flaps 26 and 27 extending from the front wall 19. Said outer end flaps are joined together as a unit for providing an end closure for the combined unit package, but are severable along the perforated line 28 extending from the perforated line 25. Thus when the double unit package is employed the front and outer end closure flaps are in effect of one piece joining and holding the units together for providing the single two hank package, but are readily severable along the lines 25, 28 to provide complete end closure flaps for the respective separated unit cartons.

The end flap 26 is notched out at 29 and the end flap 27 is notched out at 30. The notches 22 and 29, and 24 and 30 are arranged in mating relation, respectively, adjacent the front outer corners of the package to provide spaced apertures in the upper end wall through which the handle loop 10 of the clothesline may extend as shown in Fig. 1, and for the purposes heretofore set forth.

In Fig. 4 there is shown a modification of the invention wherein there is provided a single carton package having a back wall 116, side walls 117, 118 and a front wall 119, the side wall 117 terminating in a securing flap 120. Hinged to each of the side walls there are inner end closure flaps 121 and 123, said flaps being offset inwardly to provide openings at 122 and 124 respectively when said flaps are folded over in position. The outer end flap 127 is scored to provide a hinge connection with the front wall 119 adjacent which its lateral edges are curved inwardly to provide recesses 129, 130.

The carton shown in Fig. 4 is adapted to contain a pair of hanks A, B with the joining handle loop 10 extending outwardly through the openings or apertures provided between the inwardly folded end flaps wherein they are spaced apart at the notches 122, 124 and 129, 130 respectively.

The invention claimed is:

1. A package of rope hanks comprising a sheet folded upon itself to provide a pair of parallel open ended cells connected side to side by a continuous front wall, an outer end closure flap hingedly connected to said front at one end thereof and extending over the ends of said cells, the said closure flap having notches in its side edges, said front wall having a weakened line extending longitudinally thereof between said cells from one end to the other of said package and across said closure flap midway the side edges thereof, and a rope hank in each cell and a rope loop extending from one end of one of said hanks to the corresponding end of the companion hank through said notches.

2. A package of rope hanks comprising a sheet folded upon itself to provide a pair of parallel

open ended cells connected side to side by a continuous front wall, inner end closure flaps extending over the end of each of said cells respectively, each provided with a notch in a side edge thereof, an outer end closure flap for said cells overlying both of said inner end closure flaps, each side edge of said outer end closure flap having a notch therein to register with the notches in said inner end flaps, said front wall having a weakened line extending longitudinally thereof between said cells from one end to the other of said package and across said outer end closure flap midway the side edges thereof, and a rope hank in each cell and a rope loop extending from one end of one of said hanks to the corresponding end of the companion hank through the said registering notches.
